Patented Aug. 15, 1922.

FIG. 1.

FIG. 2.

FIG. 3.

WITNESS:

INVENTOR.
F.C. METZLER.

BY
J. J. DeGarmo
ATTORNEY.

UNITED STATES PATENT OFFICE.

FREDERICK C. METZLER, OF SHOSHONE, WYOMING.

TAIL-DOCKING DEVICE.

1,425,671.

Specification of Letters Patent. Patented Aug. 15, 1922.

Application filed April 8, 1920. Serial No. 372,185.

To all whom it may concern:

Be it known that I, FREDERICK C. METZLER, a citizen of the United States, residing at Shoshone, in the county of Fremont and 5 State of Wyoming, have invented certain new and useful Improvements in Tail-Docking Devices, of which the following is a specification.

This invention relates to a device for docking the tails of lambs and other small animals.

In the process of docking the tails of lambs and other animals to facilitate breeding and shearing and to promote their sanitary condition, as it is practiced at present, the wound produced by cutting the appendage with an ordinary knife is left to bleed until it is closed by natural causes. The consequent loss of blood invariably has a weakening effect upon the animal,—often resulting in its death, and the blood spurting from the wound when the tail is being docked is a source of great discomfort and annoyance to the operator who in a very short time is 20 covered with blood from head to foot.

It is the principal object of the present invention to avoid this loss of blood by providing a mechanism of very simple construction which in one operation severs the tail 25 of the animal and sears the wound produced thereby.

Another object of the invention resides in providing a device of the above described character which is portable and which may 30 be folded in compact shape for convenience in carrying it from one place to another.

With the above objects in view my invention consists in mounting a knife with relation to a chopping block and a stove adapted 35 to heat it to a cauterizing state, so that it will engage the block in one position and can be placed in the stove in another position.

In the operation of the invention an operator swinging the knife back and forth between the stove and the chopping block readily docks the tails of animals placed upon the block by helpers, the wound at the end of the stumps thereof being synchronously cauterized by contact of the metal knife blade which is constantly kept 50 in a searing condition.

An embodiment of my invention has been illustrated in the accompanying drawings

in the various views of which like parts are similarly designated, and in which—

Figure 1 represents a plan view of my improved tail docking device;

Figure 2, a sectional side elevation of the same, and

Figure 3, a transverse section taken along the line 3—3, Figure 2.

Referring to the drawings the numeral 5 designates a base made of wood or other light material upon which the elements of 65 the device are mounted in cooperative relation.

The base is preferably composed of two sections hinged together as at 3 so that they may be folded upon each other when the 70 device is not in use and thereby reduce the size thereof for convenience in packing and in carrying it from one place of operation to another.

The block upon which in the operation of 75 the device the tails of the animals are docked, consists of a piece of wood 4 which is removably fitted in a dove tailed groove 5^a at one end of the base and which may be readily replaced in case of wear or breakage. 80

The stove which is mounted at the opposite end of the base, comprises in its preferred form a heating chamber 6 provided with a hood or box 7 having a vertical slot 8 to admit the swinging knife, a pair of vapor 85 burning torches 9 extending oppositely in the chamber, and a reservoir 10 for vaporizing liquid, in connection with the torches.

The knife consists of a sharp-edged blade 12 fastened at the end of a metal helve 13 90 which at its opposite end is pivotally connected between two bearings 14 fastened to the base intermediate of the chopping block and the stove.

The helve carries a sliding grip 15 made 95 of asbestos or other nonconducting material formed around a tubular sleeve, which allows the operator to handle the cutting element without touching the heated metal parts thereof.

When in the operation of the device, the knife is in its inoperative position the blade thereof extends between the burners in the heating chamber to which it was admitted through the vertical slot in the upper portion of the hood. 105

The helve of the knife rests in a slanting position upon the lower end of the slot and

the grip is placed at a point remote from the stove by sliding it downwardly along the helve.

When the helper has placed the tail of an animal upon the wooden chopping block, the operator swings the knife upon the same by means of the sliding grip thereby severing the member and at the same time searing the wound at the end of its stump by 10 contact of the heated blade.

The knife is returned to the stove immediately after the cutting operation is completed, to be reheated until a second helper has placed the tail of another animal upon 15 the block.

The folded relation of the sections of the base and the position of the knife in the heating chamber of the stove has been shown in broken lines in Figure 2.

20 Having thus described my improved tail docking instrument in the most practical form at present known to me, I desire it understood that modifications in the construction and arrangement of its parts may 25 be made without departing from the scope of the invention.

What I claim and desire to secure by Letters Patent is:

1. A tail-docking device comprising a 30 base, a chopping block and a stove oppositely mounted thereon, and a knife pivoted between the block and the stove, to engage the block in its movement in one direction and to be heated by the stove at 35 the end of its movement in the opposite direction.

2. A tail-docking device comprising a base, a helve pivoted thereon, a cutting blade at the end of the helve, a chopping 40 block disposed to be engaged by the blade, and a stove adapted to heat the blade in an adjusted position of its helve.

3. A tail-docking device comprising a base, a helve pivoted thereon, a cutting blade

at the end of the helve, a sliding grip on 45 the helve, a chopping block disposed to be engaged by the blade, and a stove adapted to heat the blade in an adjusted position of its helve.

4. A tail-docking device comprising a 50 chopping block, a knife movably mounted to engage the same, a stove composed of a chamber having an opening to admit the knife in an adjusted position thereof, and a burner in the chamber.

5. A tail-docking device comprising a 55 chopping block, a knife movably mounted to engage the same, a stove composed of a chamber having an opening to admit the knife in an adjusted position thereof, and a blow-torch in the chamber.

6. A tail-docking device comprising a 60 chopping block, a knife movably mounted to engage the same, a stove composed of a chamber having an opening to admit the knife in an adjusted position thereof, a reservoir for gaseous fuel, and a burner in the chamber, connected with the reservoir.

7. A tail-docking device comprising a 65 chopping block, a knife movably mounted to engage the same, a stove composed of a chamber having an opening to admit the knife in an adjusted position thereof, and burners in the chamber at opposite sides of the knife.

8. A tail docking device comprising a 70 support, a chopping block and a stove at separate points thereof, and a knife mounted on the support to be movable from a determinate position in which it is subjected to 75 the heat of the stove, to a second determinate position in which it is removed from the heating influence of the stove and engages the block.

In testimony whereof I have affixed my 80 signature.

FREDERICK C. METZLER.
